US00D841873S

(12) **United States Design Patent** (10) **Patent No.:** **US D841,873 S**
(45) **Date of Patent:** **** Feb. 26, 2019**

(54) **SWIVEL DISK LIGHT**

(71) Applicant: **E. MISHAN & SONS, INC.**, New York, NY (US)
(72) Inventor: **Fred Hollinger**, Monroe Township, NJ (US)
(73) Assignee: **E. MISHAN & SONS, INC.**, New York, NY (US)

(**) Term: **15 Years**

(21) Appl. No.: **29/662,559**

(22) Filed: **Sep. 6, 2018**

(51) **LOC (11) Cl. 26-99**

(52) **U.S. Cl.**

USPC **D26/118; D26/67**

(57) **CLAIM**

The ornamental design for a swivel disk light, as shown and described.

DESCRIPTION

FIG. 1 is a front, top perspective view of a swivel disk light showing my design therefor;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, top perspective view of a second embodiment showing the disk in a rotated orientation;

FIG. 10 bottom perspective view of the second embodiment showing the disk in a rotated orientation;

FIG. 11 is a front elevational view of the second embodiment showing the disk in a rotated orientation;

FIG. 12 is a rear elevational view of the second embodiment showing the disk in a rotated orientation;

FIG. 13 is a left side view of the second embodiment showing the disk in a rotated orientation;

FIG. 14 is a right side view of the second embodiment showing the disk in a rotated orientation;

FIG. 15 is a top plan view of the second embodiment showing the disk in a rotated orientation; and,

FIG. 16 is a bottom plan of the second embodiment showing the disk in a rotated orientation.

Throughout the drawings, broken lines show environment only and form no part of the claimed design.

1 Claim, 16 Drawing Sheets
